UNITED STATES PATENT OFFICE.

NELL E. McHENRY, OF DENISON, IOWA.

ROAD SIGNAL.

Application filed July 18, 1925. Serial No. 44,541.

This invention relates to signs, particularly those adapted for use along highways, and has for its object the provision of a novel sign embodying several structural characteristics and features of advantage whereby to be a distinct improvement over those of old and well known types.

An important object of the invention is to provide a highway or road sign designed 10 to correspond to the system of routing adopted in many States and bearing indicia identifying the sign and the highway along which it is placed so that there will be no confusion in the mind of the observer.

15 Another object of the invention is to provide a sign not only bearing indicia as to direction and the like but also preferably shaped in conformity with the geographical outline of the State in which it is used, or 20 else provided with cut out portions or other means indicating the specific State.

A further object of the invention is to provide a highway sign which bears indicia as to direction, distance or the like, the specific construction being preferably such that 25 the indicia will be clearly visible at night on account of reflecting light thrown upon the sign by the headlights of an approaching vehicle.

30 The invention further contemplates the provision of various structural details whereby the different portions of the sign may be detachably connected and whereby the direction indicator may be shifted to meet the particular conditions which exist.

35 An additional object is the provision of a sign of this character which is well adapted to be constructed of metal and which will therefore be not only simple and inexpensive 40 to make but very durable in service.

With the above and other objects and advantages in view, the invention consists in the details of construction and the arrangement and combination of parts to be herein- 45 after more fully described and claimed, and illustrated in the accompanying drawings, in which:

Figure 1 is a front elevation of the complete device looking at the front thereof.

50 Figure 2 is a rear elevation.

Figure 3 is a vertical section taken on the line 3—3 of Figure 2.

Figure 4 is a horizontal section taken on the line 4—4 of Figure 2.

55 Figure 5 is a detail in cross section taken on the line 5—5 of Figure 1.

Figure 6 is a detail view showing a modification, and

Figure 7 is an elevation showing a modified form of sign plate.

Referring more particularly to the drawings I have shown the device as comprising a plate 10 of metal which is readily capable of being formed as a casting, although it is conceivable that it could be constructed as a stamping if such should be found desirable for any reason. This plate 10 constitutes the sign and a preferred feature is the fact that it is intended to have a contour corresponding to that of the particular State in

which it is used. In order that this plate will have the appearance of thickness and yet be light in weight, the edges thereof, indicated at 11 are preferably comparatively thick and beveled whereas the central portion may be thin. This is readily accomplished by making the rear side, or the forward side, whichever is preferred, concave as clearly indicated in Figure 4. This plate 10 is designed to bear any suitable or desired legends as to direction and distance to the nearest or other desired place, indications as to turns or any other warnings, the letters 12 of the legends being formed open. In addition to possessing or carrying such reading matter, the sign is also intended to have a numeral cut out or formed as an opening, which numeral is designated by 13. In actual practice, this numeral is intended to refer to the particular route which the sign is intended to mark in correspondence with directions in guide books or the like or indications given on road maps.

Mounted against the rear side of the plate 10 forming the sign is a sheet or pane of glass 14 of any desired color, such for instance as green, except that in dangerous places red may be preferable and the front-surface of this glass may be formed prismatic or roughened so as to have more or less of a reflecting quality. To protect the glass pane against breakage it is preferable to provide a metal plate 14' at the rear thereof. Obviously, when the sign is viewed from the front and light is at the rear the legends on the sign will be clearly visible as the red or the other color will show through the cut out letters and numerals. The means for holding the glass pane or sheet and the protective metal plate in position may consist of a plurality of lugs 15 formed integrally upon the rear side of the plate 10, and to

prevent withdrawal of the glass pane and plate from position it is preferable to provide a strip 16 of angular formation held in place upon the sign plate as for instance by means of screws or bolts indicated at 17. Obviously, it is intended that the glass pane and plate be slid longitudinally into place, subsequently to which the strip 16 is applied and secured to effect the desired holding action. Of course, all the lugs 15 are of angular formation so that portions thereof will overlap or overhang the metal plate and prevent it and the glass from displacement. The advantage in having the front or exposed 15 surface of the glass of a prismatic or roughened nature is so that when headlights shine upon the sign at night a certain amount of the light will be reflected by the glass exposed by the cutout letters and numerals so 20 that the legends or other markings will be clearly visible to the motorists or other traveler.

In case it is not desired, for any reason, to construct the sign in the shape of a State, 25 I may resort to the arrangement disclosed in Figure 7 in which it will be observed that the construction is identically the same as above described except that the contour of the State is indicated by slots or openings 30^a 10^a in the plate 10^b, the plate itself being of rectangular or any other desired shape. In this instance the plate is also represented as having holes 10^c therein for the passage of suitable securing members such as nails or 35 the like whereby the sign may be mounted upon any suitable support.

At the top of the plate 10 it is preferable to provide a boss or upstanding projection 18 upon which is mounted an arrow or other 40 pointer 19 which may obviously be adjusted to point in the desired direction corresponding to any markings which may be provided upon the sign plate. This arrow is represented as held in place by a suitable bolt 20 45 passing therethrough and into the boss or projection 18. Instead of this being a bolt it may just as well be a stud carrying a nut 21. Of course after the arrow is once adjusted to point in a desired direction it is 50 clamped firmly in place as it is not intended that it should be subsequently moved.

While any desired means might be provided for supporting the sign I have, in Figure 1, shown it as mounted upon a reduced 55 extension formed on the upper end of a pedestal or post 22 by means of a socket member 23 formed integrally upon the lower edge of the plate 10. A set screw 24 or the like may be provided for effecting a positive 60 securing and preventing the sign from un-

desired movement. Obviously, the post 22 may be of such form as to be embedded within concrete indicated at 25 and in this instance its lower end is preferably provided with a reduced extension 26. In some instances, the post may be mounted by driving it into the ground beside a highway and in this case the construction might be such as that illustrated in Figure 6 wherein I have shown a post 27 simply having its lower end pointed as shown at 28 so as to be driven easily into the ground. Regardless of this detail, however, a convenient construction is that the post or pedestal be made as a casting and that it consists of or be provided with radial or intersecting ribs 29 which will possess the necessary rigidity while being light in weight.

From the foregoing description and a study of the drawings, it will be apparent 80 that I have thus provided a novel and attractive sign well adapted for use in marking highways in accordance with a certain predetermined system. A distinct feature of advantage is that owing to the provision 85 of the colored glass exposed at the cut out legend any matter appearing on the sign will be clearly visible by day and by night especially owing to the reflective quality of the glass where exposed which makes it possible for it to throw back a portion of the light falling upon the sign from headlights of motor vehicles or the like. It is believed that the construction and advantages will be 90 readily apparent to one skilled in the art 95 without further elaboration.

While I have shown and described the preferred embodiment of the invention, it should be understood that I reserve the right to make such changes in the form, construction and arrangement of parts as will not depart from the spirit of the invention or the scope of the subjoined claim.

Having thus described the invention, I claim—

A sign plate comprising a cast metal body having a flat rear surface formed with longitudinal ribs defining a substantially rectangular area, said ribs having overhanging flanges, said metal body being provided with a plurality of openings of a shape to define indicia, and a reflecting member disposed against the flat rear side of the body and retained within said flanges, the front face of the sign being concaved and the front face 110 being further formed with an overhanging flange located above the area provided with openings.

In testimony whereof I affix my signature.

NELL E. McHENRY.
